RIBBON-TRIMMED TEXTILE FABRIC

Abraham Goodman, New York, N. Y.

Application June 9, 1954, Serial No. 30,883

Term of patent 7 years

(Cl. D92—1)

Fig. 1.

Fig. 2.

Fig. 3.

To all whom it may concern:

Be it known that I, Abraham Goodman, a citizen of the United States of America and resident of New York, county of Queens, and State of New York, have invented a new, original, and ornamental Design for a Ribbon-Trimmed Textile Fabric, of which the following is a specification, reference being had to the accompanying drawing, forming part thereof.

In the drawing:

Fig. 1 is a face view of a ribbon-trimmed textile fabric embodying my new design.

Fig. 2 is an enlarged detail view showing several loops forming part of the fabric of Fig. 1, and

Fig. 3 is a section on the line 3—3 of Fig. 2.

I claim:

The ornamental design for a ribbon-trimmed textile fabric, substantially as shown.
